HORSESHOE OR SIMILAR ARTICLE

Leo F. McGraw and Clarence McGraw, both of 11 N. Center St., Joliet, Ill.

Filed Feb. 2, 1960, Ser. No. 59,231

Term of patent 14 years

(Cl. D54—5)

Fig. 3.

Fig. 5.

Fig. 6.

Fig. 1 is a front face view of a horseshoe showing our new design;

Fig. 2 is an edge view thereof;

Fig. 3 is a cross-sectional view taken on line 3—3 of Fig. 1;

Fig. 4 is a cross-sectional view taken on line 4—4 of Fig. 1;

Fig. 5 is a cross-sectional view taken on line 5—5 of Fig. 1; and

Fig. 6 is a cross-sectional view thereof taken on line 6—6.

We claim:

The ornamental design for a horseshoe or similar article, as shown.
